[57] CLAIM

The ornamental design for a mobile dispenser rack, as shown and described.

DESCRIPTION

FIG. 1 is a perspective view of a mobile dispenser rack showing my design;

FIG. 2 is a left side elevation view thereof;

FIG. 3 is a front elevation view thereof;

FIG. 4 is a rear elevation view thereof; and

FIG. 5 is a top plan view thereof;

The broken lines shown in FIG. 1 of the drawing are for illustrative purposes only.
